UNITED STATES PATENT OFFICE.

OSCAR KUPFERMAN, OF BROOKLYN, NEW YORK.

ELECTRIC SWITCH.

Application filed October 23, 1925. Serial No. 84,295.

This invention relates to electric switches, particularly those known in the trade as canopy switches, and has for its object to provide a switch for the control of circuits through a plurality of units of an electric system, such as lamps, whereby, through a continuous rotary motion in the same direction, the circuits through the different units will be consecutively closed or opened.

10 I accomplish this object by providing a ratchet wheel shaped commutator in which all teeth but one are conductive and which cooperates with as many contact members as there are conductive teeth, one of the 15 contact members being adapted to be connected to one pole of each unit and the other contact members with the other pole of the respective units.

When my switch is applied to a lamp 20 fixture having, for instance, two incandescent lamps, it is possible by a continuous rotation of the commutator thereof in the same direction to simultaneously light one lamp and extinguish the other or vice versa 25 or simultaneously light or extinguish both lamps.

Another object of my invention is to simplify the construction of the switch and of its individual parts, so as to reduce the 30 cost of manufacture thereof to a minimum.

With these objects in view, my invention consists in the construction, combination and arrangement of parts as will be hereinafter more fully described and defined in the 35 appended claims.

In the accompanying drawing in which similar reference characters denote corresponding parts, Fig. 1 is a cross-sectional view of the switch; Fig. 2 a longitudinal section thereof; Fig. 3 a cross-section 40 through the operating spindle with the front plate or cover removed showing the commutator and the contact pieces in operative position, and Fig. 5 a rear view of the commutator.

As one embodiment of my invention, I shall describe a switch to be used for the control of two electric lamps, but it is to be understood that my switch may be made 50 to control more than two lamps and that it is applicable for the control of other electric units than lamps.

10 denotes a substantially rectangular casting preferably composed of two plates 10^a, 10^b of bakelite or other insulating material 55 adapted to be permanently secured to one another in the manner hereinafter described. The plate 10^a is formed on its inner face with a central cavity 10^c from three corners of which lead horizontal lateral grooves 11 60 into smaller cross cavities 12, which with their outer ends terminate at the longitudinal edges of the plate 10^a and are open. Fitted in these latter cavities, are the U-shaped ends 13^a of the resilient metal members 13, which extend through the grooves 11 into said central cavity 10^c and in the latter are curved so as to tightly engage 65 around three ratchet teeth of a commutator wheel 14. This wheel is made of insulating material, preferably fibre, and according to the present example is formed with four ratchet teeth, the circumferential surfaces 14^c of which are curved eccentrically relative to the axis of the wheel. This wheel 70 is adapted to loosely bear with its flat back on the bottom of the cavity 10^c and is provided in its front face with a central square cavity 14^a to form a socket for a square spindle 15, which serves for the manipulation 75 of the commutator. The conducting element of the commutator is formed of a substantially circular plate 16 provided with three radial extensions or arms 16^a projecting from the periphery thereof, each arm 80 being at its free end somewhat broadened, as at 16^b, and so ad-measured and curved as to snugly fit around the curved surfaces of three of the ratchet teeth 14^a of the commutator, while the fourth tooth 14^b remains 85 uncovered and is, therefore, non-conductive.

The second plate 10^b serves as a cover and is centrally perforated, as at 10^d, to form a passage for the spindle 15. This cover is adapted to be permanently secured 90 in position over the plate 10^a by a clamping member 17 consisting of a metal plate formed with marginal extensions 17^a adapted to be bent around the rear plate and to be compressed into grooves 10^e of the latter. 100 The metal plate 17 is also formed with a central perforation 17^b terminating in an externally threaded forwardly projecting sleeve 18 fixed to said clamping plate 17.

The spindle 15 in its major part is of square cross-section and is adapted to fit with its inner end in the square cavity 14^a of the commutator 14 and to be centered and held 5 in position therein by said sleeve. The front or outer end 15^a of said spindle 15 is of cylindrical shape somewhat reduced in diameter and adapted to project outwardly through an opening 18^a of the sleeve 18 to 10 receive a knob 19 fixed thereon.

The switch is adapted to be fastened to a bracket of a lamp fixture or the like, which, according to the present example, is accomplished by means of two clamping 15 nuts 20, 20^a working on the sleeve 18.

The electric wires 21 for the electric system are conductively connected to the contact members 13 by soldering their ends and the U-shaped ends 13^a of the latter in the 20 cavities 12 or in any other suitable manner.

The operation of the switch is as follows:

During the rotation of the spindle 15 by its knob 19 continuously in a certain direction, the resilient members 13 will slide 25 over the surfaces 14^c of the commutator. When the commutator is given a turn to the extent of one tooth and one of the contact members comes into contact with the non-conductive tooth 14^b, there will be a break 30 of the circuit through one of the units leaving the circuit through the other unit intact or closing it, if it had been previously opened and vice versa. When on a further turn to the same extent the non-conductive 35 tooth is replaced by a conductive tooth, the circuit through the unit mentioned will be again closed and that of the other unit opened. On a further similar turn in the same direction, the circuits through both 40 units may be opened, and finally on a further turn, the circuits through both units may be closed or vice versa.

It will be noted that by providing the 45 commutator wheel with a cavity instead of an opening passing through the rear of the wheel, the spindle will be entirely insulated from the conducting sheath or plate 16. Thereby the construction becomes greatly simplified, in so far as additional or separate 50 insulating means that otherwise would be required in order to prevent short circuits through accidental contact between the rear end of the spindle and the sheath will be dispensed with. Furthermore inasmuch as 55 the position of the spindle in the cavity 14^a is fixed, no special stops, such as collars or the like on the spindle, are necessary and, therefore, by making the spindle entirely of 60 square cross-section at least one or two steps in the manufacture thereof are eliminated.

What I claim is:—

1. As an article of manufacture, a rotary switch comprising a comparatively flat casting composed of two superposed plates of insulating material bearing on one another,

the rear or lower plate being grooved centrally and laterally and the front or upper plate being centrally perforated, a ratchet shaped commutator wheel loosely bearing on the bottom of the central groove of the 70 rear plate, a sheath of conductive material covering the bearing surface of said wheel and all teeth thereof but one, resilient contact members cooperating with said teeth, the number of said contact members corresponding to that of the sheathed teeth of 75 said wheel, said contact members projecting into and being fixed in the lateral grooves of said rear plate and conductively connected therein to the wires of the electric system, a 80 centrally perforated member extending over the front plate and having its end portions bent around the sides and the back of the rear plate to clamp said two plates together, a threaded sleeve centrally fixed to and projecting from said clamping member, a spindle 85 rotatively borne in said sleeve and engaging said ratchet wheel and clamping nuts working on said sleeve and serving for clamping said switch in position of use to a 90 stationary object.

2. As an article of manufacture a rotary switch comprising a comparatively flat casting composed of two superposed plates of insulating material bearing on one another, 95 the rear or lower plate being grooved centrally and laterally and the front or upper plate being centrally perforated, a ratchet wheel shaped commutator loosely bearing on the bottom of the central groove of said rear plate, said commutator having a central square groove, a sheath of conductive material covering the bearing surface of said wheel and all teeth thereof but one, resilient contact members cooperating with said teeth, 100 the number of said contact members corresponding to that of the sheathed teeth of said wheel, said contact members projecting into and being fixed in the lateral grooves of said rear plate and conductively connected 105 therein to the wires of the electric system, a centrally perforated member extending over the front plate and having its end portions bent around the sides and the back of the rear plate to clamp said two plates 110 together, an externally threaded sleeve projecting centrally from said clamping member, a spindle relatively borne in said sleeve and being of square cross section to fit in said square groove of said commutator and 115 means on said sleeve for clamping said switch to a stationary object.

3. As an article of manufacture, an electric canopy switch comprising a casing composed of two comparatively flat superposed plates of insulating material, the rear plate being grooved centrally and laterally and the front plate being centrally perforated, a commutator loosely bearing in the central groove of said rear plate, contact members 125

cooperating with said commutator and fixed in the lateral grooves of said rear plate and connected therein to the electric system, a centrally perforated member extending over the front plate and having its end portions bent over the sides and back and thereby clamping said two plates together, a sleeve projecting centrally from said clamping

member, a spindle borne in and centered by said sleeve and operatively engaging said commutator and means on said sleeve for clamping said switch to a stationary object.

In testimony whereof I affix my signature.

OSCAR KUPFERMAN.
